Attorney

UNITED STATES PATENT OFFICE.

CHARLES W. TAYLOR, OF SALT LAKE CITY, UTAH, ASSIGNOR TO EMILIUS C. F. HARTMANN AND DAVID NEFF, BOTH OF SALT LAKE CITY, UTAH.

SOUND AMPLIFIER.

Application filed April 22, 1925. Serial No. 25,065.

This invention relates to a sound amplifier particularly adapted for use in connection with radio receivers, and its principal objects are to provide an instrument which shall—

First, be highly efficient and capable of producing maximum sound amplification.

Second, be compact in form so as to occupy a minimum space.

Third, be inconspicuous, though ornamental in appearance.

Fourth, be reasonable in cost.

I attain these objects by means of a plurality of hollow truncated conical bodies or receptacles of gradually increasing sizes constituting frustro-conical sections, which are placed one within the other in alternating inverse order, that is to say, the smallest or initial frustro-conical body is placed with its flaring larger end within the next larger or secondary frustro-conical body in proximity to the smaller end of the latter. The second frustro-conical body is then placed with its larger end inside the next larger frustro-conical body and in proximity to the smaller end of the latter, and so on, the final frustro-conical section constituting the bell. The walls of the successive frustro-conical bodies are so placed that the bodies themselves shall not be in contact, but that there shall be an annular open space between the larger portions of the interior cones, and the smaller portions of the circumscribing cones. Opposed to the flaring end of each of the hollow truncated conical bodies is a solid deflecting surface or surfaces, by which sound waves emerging from the flaring end of any of the conical sections, are reversed in direction, and caused to assume a path through the next larger conical section until the sound waves finally emerge at the flaring mouth of the last and largest conical section, where they may encounter a directing surface which causes the sound waves to be projected into space in all directions from the axis of the instrument.

The advantages secured by this method of construction are that: (a) an amplifying horn of considerable length can be substantially cut up into sections, and the sections be virtually nested to occupy very much less space and length than the original horn; (b) the successive amplifying sections, being independent of each other, have each pro-

gressively increasing amplifying effects upon the sound waves emerging from the next preceding sections.

The features of this invention for which the protection of Letters Patent is desired, are collectively grouped in the claims forming the conclusion of this specification.

In the drawing, which illustrates merely one embodiment of this invention,

Fig. 1 represents a vertical center section; 60

Fig. 2 an elevation, viewed in the direction of either of the arrows 2, in Fig. 1;

Fig. 3, a bottom plan view of the bell portion of the device, taken separately, and

Fig. 4, a top plan view of the secondary 70 or stand portion thereof, also taken separately.

Throughout the drawing, similar parts are designated by similar reference numerals.

Referring to the drawing, 20 represents the stand portion having the outstanding flange 21 forming a foot. Projecting upwardly from the foot is the secondary frusto-conical hollow section or cup 24, which is inverted, and at its bottom has the cone 25, which is preferably arranged substantially concentric with the axis of the cup, and whose outer surface is joined to the conical interior surface of the cup by means 80 of the curved transition surface 26.

Spaced apart both upwardly and outwardly from the upper edge 27 of the cup, is the bell 28. In general, the bell 28 also has the form of the frustum of a cone, this 90 cone surrounding the conical cup 24, as shown in Fig. 1. The bell 28 is supported upon the upper rim of the cup 24, by means of the legs 29, whose upper portions 30 are firmly imbedded in the solid upper base portion 31 of the bell. Extending downwardly from the base 31 is the initial frusto-conical section 32 whose flaring base rim is spaced apart from the interior surface of the conical cup 24 as shown in Fig. 1. The 100 interior surface of the wall of bell 28 may consist of the portions 33 and 34, which make a slight angle with each other vertically. The portion 33 may be joined to the outer wall surface of the cone 32 by means of the transition curved surface 35. The bell 28 is surmounted by the hollow cap 36 which is fitted tightly thereto, along the contacting surfaces 37. The cap 36 provides a chamber 38 in which may be placed 110

suitable telephone receiver whose position is indicated by dotted lines 39. The receiver may have a collar 40 through which the sound passes into the throat 41, which forms 5 virtually a continuation of the space within the cone 32.

In operation, the sound waves from the receiver pass downwardly through the throat 41 as indicated by the arrows, through 10 the interior of the cone 32, and strike the surface of the cone 25, being thereby deflected around the transition curved portion 26, and so reversed in direction to pass upwardly through the interior of the cone 24, 15 after which the sound waves are again deflected and reversed by the surface 35 and are caused to pass downwardly around the transition curved portion 42, and out into the surrounding space as indicated by the 20 arrows. Holes 43 may be provided in the upper base of the bell 28 for the purpose of conducting away any sound waves that may be projected thereinto from the receiver 39. These latter sound waves flow into and 25 join the main volume of sound waves as they round the transition surface 35. The base structure may be connected to the bell structure by means of the wires 45, which pass through each structure and are fitted 30 tightly into the same. The cup structure 24, bell structure 28 and the cap 36 may all be made of material having desirable tonal qualities, such as wood or hard rubber.

It is desirable that the elements of the 35 conical surface 34 and the elements of the surfaces of cones 24 and 32 shall all make angles equal to each other with the common axis of the same. Also, it is desirable that the circuitous passage for the sound 40 waves, formed between the opposing walls of the successive frusto-conical sections, shall be progressively of uniformly increasing area of cross-section from the throat to the bell, as nearly as possible.

45 The wire legs 29 with feet 50 resting on the rim 27 of the cup, and the fastening wires 45, provide great flexibility between sections 32, 24 and 34, by means of which the principles of resonance are given every 50 latitude to assert themselves. This causes section 24 to strengthen the sound produced by the vibration of section 32, and again, causes section 34 to strengthen the sound produced by the vibration of section 24. 55 No matter how many sections are used, the outer sections all operate to strengthen the sound caused by the vibrations of the next inner sections provided the sound originates at the innermost section.

60 While a specific embodiment of this invention is herein shown and described, it is to be clearly understood that all the detailed parts thereof, may, or may not, be shown in the preferred forms, and further, 65 that the preferred forms may be varied from

time to time, as the development of this invention and the arts to which it appertains, progress. Therefore, that which forms an essential and characteristic part of this invention will be readily discernible from the 70 claims in which its spirit is generalized.

Having fully described my invention, what I claim is:

1. A sound amplifier comprising a plurality of hollow bodies of gradually increasing sizes relatively to each other, placed one within the other in alternating reverse order and spaced apart from each other to define a circuitous passage for sound waves, and flexible connections between successive ones of 80 the said bodies. 75

2. A sound amplifier, comprising a stand portion, a secondary hollow frusto-conical section extending upwardly therefrom; a sound deflector in the bottom of said frusto-conical section, an initial frusto-conical section projecting inwardly of the said secondary section, a final frusto-conical section surrounding the said secondary section in spaced relation thereto, means for projecting 90 sound waves into the said initial conical section, and means for flexibly supporting the initial and final said sections relatively to the said secondary section. 95

3. A sound amplifier comprising a final frusto-conical section having an upper base, an initial frusto-conical section depending inwardly from the said base in spaced relation to the said final section; a stand having an upwardly extending frusto-conical section projecting into the space between the said initial and final frusto-conical sections, and means for flexibly supporting the initial and final said sections relatively to said stand. 100

4. A sound amplifier comprising a stand, a cup projecting upwardly therefrom, a sound deflector in the bottom of the said cup, an initial hollow sound-conducting body above the said deflector and spaced apart therefrom; a bell surrounding the said cup in spaced relation thereto, a second sound deflector leading to the said bell, said second deflector located above the rim of the said cup, and a flexible connection between the 110 said bell and the said stand. 115

5. A sound amplifier comprising an initial hollow section, a final bell section surrounding, and spaced apart from the said initial section, a base joining the two said sections to each other, legs projecting inwardly from said base, a hollow cup section projecting into the space between the said initial and bell sections, feet projecting from said legs arranged to rest on the rim of said cup, and means for flexibly holding said bell in fixed relation to said cup. 120

In testimony whereof I sign my name hereto.

CHARLES W. TAYLOR.
